UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP.

LOOSE-LEAF LEDGER.

Application filed September 19, 1922. Serial No. 589,080.

To all whom it may concern:

Be it known that I, JOHN SCHADE, a citizen of the United States, residing at the city of Holyoke, county of Hampden, and State of Massachusetts, have invented certain new and useful Improvements in Loose-Leaf Ledgers; and I do declare the following to be a full, clear, and exact description of the invention, such as will enable others skilled in the art to which it appertains to make and use the same.

This invention relates to certain new and useful improvements in loose leaf ledgers, and the primary object thereof is to provide a ledger wherein the angle sections carrying the side cover members constitute the back, thereby dispensing with the necessity of providing a special back for the ledger, and one wherein the central pivot rod about which the angle sections and side cover members are hinged or swing, is employed to control or release the means which locks or latches the sections together.

The invention still further aims to provide a ledger construction which when open enables the leaves to lie more nearly flat or horizontal and which also enables the side cover members to be made on a standard machine.

Still further, the invention aims to improve the securement of the prongs and to provide a locking mechanism which is efficient and devoid of parts subject to becoming loose or rendered inoperative.

The invention has still further and other objects which will be later set forth and manifested in the course of the following description.

In the drawings:—

Figure 1, is an end elevation of the invention;

Figure 2, is a section on line 2—2 of Figure 1;

Figure 3, is a section on line 3—3 of Figure 2;

Figure 4, is a top plan view of the ledger in open position;

Figure 5, is a section on line 5—5 of Figure 4;

Figure 6, is a detail sectional view of a modified form of releasing means, and

Figure 7, is a detail view of a modified

form of stop for limiting the movement of the operating rod.

In proceeding in accordance with the present invention, a pair of angular metal back sections 1 and 2 are employed to which the side cover members 3 and 4 are suitably secured, the adjacent sides of the sections being formed with hinge knuckles 5 that receive the combined pintle-forming and lock-releasing rod 6. Rod 6 is equipped with a radially extending finger piece 7 by means of which the rod is operated. Riveted to the angular back sections are the substantially L-shaped latching members 8 and 9, member 8 being resilient while member 9 is rigid. The resilient member 8 has its free or effective end turned over as indicated at 10 and then extended outwardly to form a stop 11, the latter located at about the center of the end 10. The turned over end 10 forms a resilient latch member which engages with a latch 12 which is rigid and extends outwardly from the free end of the rigid member 9. It will thus be seen that the latch 11 of member 8 will snap over the latch 12 of member 9 and lock the two angle sections together.

For the purpose of releasing the latch 11 from engagement with the latch 12, a sleeve 13 is rigidly secured to the rod 6 and carries a releasing member 14, the free end of the latter engaging the resilient latch 10 to compress or force the latch out of engagement with the latch 12, thereby releasing the angle sections and permitting opening of the ledger. The latch 12 and member 9 are bifurcated at 15, to allow the releasing member 14 to pass and thereby permit full opening of the ledger.

The stop 11 acts to engage the releasing member 12 so as to prevent overthrowing of the latter with respect to the resilient latch member 10. This stop 11 is not necessary although it may be used and its use is preferable in order to prevent overthrowing of the releasing member by careless or indifferent users.

As depicted in Figure 6, a modified form of releasing means is disclosed, and in which in lieu of the sleeve 13, a pin 20 may be employed which may be riveted in an opening provided therefor in the rod 6', the latter

corresponding to the rod 6 in the other views of the drawing. With this modified structure, the adjacent hinge knuckle is formed with a transverse slot 21, through 5 which the pin 20 projects.

As a modified form of stop, in cases where the use of a stop is desired, the hinge knuckle 5' adjacent to finger piece 7' may be cut away on its outer end as indicated at 22 10 in Figure 7 so as to engage the finger piece and thereby limit turning movement of the rod 6" accordingly. The knuckle, finger piece and rod correspond to the similar parts in the remaining figures.

15 For the purpose of enabling the leaves to lie more nearly flat or horizontal, it will be seen that the outer ends of the angle sections 1 and 2 are bent outwardly at 25, or relatively diverge, which greatly contributes 20 toward flat disposition of the leaves when the ledger is open. As depicted in Figure 5 of the drawing since should the ends work up, the free edges thereof cannot catch in the leaves the prongs 26 are provided with 25 shoulders 27 which are swaged thereon, following which the prongs are riveted as shown at 28 to the angle sections 1 and 2.

From the foregoing it will be seen that the back of the ledger is provided by the adjacent parts or sides of the angle sections 1 and 2 and that the latter not only carry the latching means 8 and 9, but in addition the rod 6 which acts in a dual capacity, namely to afford a hinge pintle for the knuckles 5 of the angle sections and also means for supporting and operating the releasing member 14 or 20 of the latching device. It will be further seen, that the releasing member is so mounted on the rod 6 or 6', so as to cooperate with the hinge knuckles to prevent any lengthwise movement of the rod with respect to the structure.

What is claimed is:

1. In a loose leaf ledger, angular back sections, a rod pivotally connecting the sections, latch members secured to the back sections and being disposed to substantially aline when the ledger is in closed position, one of the latch members having a substantially U-shaped free end formed with a lateral stop and the other latch member having a catch formed to engage with the stop, the second named latch member having a slot located adjacent to said rod, and a releasing member rigid on the rod and movable in the slot to engage said U-shaped end of the latch member to disengage same from the catch and having its movement limited by engagement with said stop.

60 2. In a loose leaf ledger, angular back sections, a rod pivotally connecting the sections, latch members secured to the back sec-

tions and being disposed to substantially aline when the ledger is in closed position one of the latch members having at its free end turned over and the other latch member having a catch form to engage the extremity of said turned over free end, the second named latch member having a slot, and a releasing member on the rod movable in the slot and engageable with the turned over end of the first named latch member.

3. In a loose leaf ledger, angular back sections, a rod pivotally connecting the sections, latch members carried by the sections and having interengaged parts, and releasing means carried by the rod and having a free part to wipingly engage one of the latch members to effect disengagement of the interengaged parts of the members.

4. In a loose leaf ledger, angular back sections, a rod pivotally connected to the sections along the edge portions of one side of the sections, cooperating latch members secured to the other sides of the sections and disposed to lie substantially parallel to the first named sides of the sections when the parts are in ledger-closed position, and means carried by the rod to release the members from latched position.

5. In a loose leaf ledger, angular back sections, a rod pivotally connecting the sections, cooperating latch members carried by the sections and disposed to lie in a substantially straight line extending across the rod and having interengaged parts disposed opposite adjacent to the rod when the ledger is in closed position, and releasing means to disengage the latch members carried by the rod.

6. In a loose leaf ledger, angular back sections, a rod pivotally connecting the sections, cooperating latch members carried by the sections and disposed to lie in a substantially straight line extending across the rod and having interengaged parts disposed opposite adjacent to the rod when the ledger is in closed position, and releasing means carried by the rod and having a free part wipingly engaged with one of the latch members to disengage the latter.

7. In a loose leaf ledger, angular back sections, a rod pivotally connecting the sections, latch members having parts formed to automatically snap into engagement with each other at a point substantially opposite to the rod and at a point at approximately the center of the lengths of the rod, and means carried by the rod to engage the latch members and release same.

In testimony whereof I affix my signature hereto.

JOHN SCHADE.
